UNITED STATES PATENT OFFICE.

ALEXANDER W. BIDDLE, OF PHILADELPHIA, PENNSYLVANIA.

FOOTWEAR.

No. 888,458.

Specification of Letters Patent.

Patented May 26, 1908.

Application filed March 23, 1908. Serial No. 422,588.

To all whom it may concern:

Be it known that I, ALEXANDER W. BIDDLE, a resident of Philadelphia, in the county of Philadelphia and State of Pennsylvania, 5 have invented certain new and useful Improvements in Footwear, whereof the following is a specification, reference being had to the accompanying drawings.

The object of my invention is to so construct a shoe or boot, as to efficiently protect the wearer against currents of electricity.

Under the present existing conditions involving the wide spread use of dangerous 15 electrical currents, it is highly desirable that any one, not only motormen, linemen, and others, directly employed in the handling of electrical devices, should be able to carry on their work with substantial immunity, but 20 that ordinary persons, ignorant of the danger to which they are daily exposed, should be protected against accident from electrical currents. Ordinarily, the circuit which is fatal or injurious to a human being is completed through the feet, and hence in order 25 to afford protection, efficient electrical insulation must be provided at that region. Shoes made completely of rubber or having the soles and heels entirely of rubber, though 30 affording insulation, are, as is well known, uncomfortable to the wearer, as well as unhealthy under some circumstances; do not afford a secure footing on wet smooth surfaces; and lack the durability which is 35 desirable for every day wear.

Shoes having leather soles do not afford effective insulation, even when not saturated with moisture from external sources, since the perspiration of the foot tends to dampen 0 the sole, and, being somewhat saline in its character, the retained dampness renders the leather and stitching distinctly conductive. The mere addition of a non-conducting element, such as rubber or mica, &c., to an 5 ordinary leather sole, as has been employed for water-proofing purposes, does not insure protection, because of the existence of certain weak points in the insulation of shoes of this character, as heretofore constructed.

My present invention embodies a combination with the desired leather elements, which go to make up a serviceable shoe, of insulating elements so organized as to present no weak spot in the insulation, and 5 hence I am enabled to interpose between the

foot of the wearer, and the ground or other conductor, a structure which is practically of such high resistance throughout its entire interposed portion as to afford complete and effective insulation.

In the accompanying drawings, Figure I, represents in side elevation a shoe embodying my invention. Fig. II, is a vertical transverse section through the foot on the line II, II, of Fig. I. Fig. III, is a vertical 65 transverse section through the heel and adjacent portion of the upper, on the line III, III, of Fig. I.

Referring to the drawings,—1, represents the upper of an ordinary leather shoe, having the usual thin insole 2, and provided with what may be considered as an ordinary double sole, composed of the inner sole 3, and thick outer sole 4. The inner sole 3, is stitched to the upper, in the usual manner. 70 The stitches which unite the outer sole 4, to the inner sole 3, are located in recesses or grooves 5, so as to be embedded within the leather itself and above the bottom surface of the sole. These grooves, after the stitches 75 have been sewed, are filled with insulating material, such as rubber cement, &c., indicated by the heavy cross section lines in the grooves 5, so that moisture cannot reach the stitches. Interposed between the inner sole 80 3, and the outer sole 4, is a continuous sheet or layer of insulating material 6, such as rubber, asbestos &c., which extends, as shown, throughout the entire length of the shoe, including the region above or through the heel. 85 The stitches 7, of course pass through this sheet, but, since said stitches are themselves insulated by the cement or other non-conducting filling within the grooves 5, they do not practically detract from the efficient 90 insulation.

The heel 9, may be built up in the usual manner by a number of leather pieces which may be secured together by nails 10, arranged in series, as indicated at 10, 11, and 12. The 100 respective series, however, are arranged in staggered relation, so that the metal of one series does not touch that of another, and hence, the conductivity of the heel as a whole, is limited by the existence of leather portions between the metallic ones. The nails of the uppermost series 12, pass through the insulating sheet 6, in order to secure the heel to the inner sole 3, which is extended throughout that region. To meet the condition thus 105 110

created, I interpose at the region of the heel, and preferably extending slightly beyond it, a secondary insulating sheet 13, which is located above the ends of the nails and which 5 may be covered by the insole 2, or by a separate layer of thin material. Hence, it will be seen that there is a complete and practically imperforate layer or sheet of insulating material, directly below the foot, 10 throughout the entire length and width of the shoe, and that the only places where said sheet is traversed by an element which might act as conductors (i. e. the stitches in the soles and the nails in the heel), are protected by a secondary insulation of the character described. 15

The shoe as thus constructed is neat in appearance and entirely comfortable, since the insulating elements are completely shielded 20 from what might be unpleasant proximity to the foot. Incidentally they may tend to make the shoe water-proof, but this of course, is a secondary advantage and not the direct result aimed at.

25 Having thus described my invention, I state that I do not broadly claim the use of rubber or insulating material for the sole or heel of a shoe, for I am of course aware that rubber, mica, &c., have been employed heretofore for water-proofing purposes. Nor do 30

I even broadly claim such material as an element in the structure of the heel or sole.

I believe that as heretofore employed, even though it may have accidentally had some tendency toward electrical insulation, 35 the elements have not been so organized as to completely and effectively protect the wearer against electric currents.

I claim:—

The combination with the upper, of an inner sole secured thereto, an outer sole provided with grooves and secured to the inner sole by means of stitches embedded in said grooves; an insulating filling for said grooves; a primary sheet of insulating material co-extensive with the inner sole and arranged below the same; a heel secured to said inner sole, the layers of said heel being secured by non-continuous fastening elements; and a secondary sheet of non-conducting material 50 arranged above the primary sheet at the region of the heel, substantially as set forth.

In testimony whereof, I have hereunto signed my name, at Philadelphia, Pennsylvania, this twenty-first day of March, 1908. 55

ALEXANDER W. BIDDLE.
